CRANK BALANCED UNIT

Edgar W. Patterson, Long Beach, Calif.

Application November 27, 1940, Serial No. 367,348

12 Claims. (Cl. 74—591)

The present invention relates generally to balanced units as used in the oil well industry for pumping wells, and more particularly to certain improvements whereby the shaftless gear unit of my application filed September 3, 1940, under Serial Number 355,159 may be utilized in the crank balancing of a pumping unit.

In my above mentioned application, I disclosed a gear unit having a shaftless low speed member with the purpose in view of promoting various economical and operating advantages over previous gear units as utilized in this field, and as therein disclosed, the gear has been proven to be readily and advantageously usable with air balanced pumping units and weight balanced pumping units of the type known as beam balanced units or in other words those wherein the balancing weights are mounted on or attached to the walking beam.

There is, however, another type of weight balanced pumping unit known as a crank balanced unit and it is my present general aim and purpose to provide a means adapting my improved shaftless gear unit to this type of balanced pumping unit in a practical manner which will not only permit of the practical, advantageous use of the shaftless gear unit in the crank balancing of pumping unit, but will also provide certain practical advantages in the use of the balancing cranks themselves.

In my above mentioned application I disclose a gear unit in which the low speed member is in the form of a gear ring wholly supported by a peripheral bearing and without a shaft. The gear ring has radially inwardly projecting crank pin supports, a crank pin through one of which supports is directly attachable to the lower bearings of the pitmans commonly employed as a means of transmitting relatively slow reciprocating movements to the walking beam.

According to my present improvements the crank pin supports of the above gear ring, extending within its peripheral bearing, are eliminated and balancing cranks are attached to the gear ring in a manner which adapt the same to swing at opposite sides of the gear unit in an arc of movement the same as at present, though in much more closely spaced relation than cranks attached to the outstanding ends of the low speed shaft of present units which are necessarily of substantially greater width than the gear unit of this invention.

In attaching the crank or crank arms to the low speed gear ring, it is an object of the present improvement to do so in a manner which will 55 presently see.

permit of their ready disconnection from the gear ring, without removing the cranks whenever it may be necessary to rotate the gear ring without rotating the cranks and their weights.

With the above general statements and objects of the invention in mind, it is believed it will be better understood and more thoroughly appreciated from the following description in detail of the mode thus far considered best for carrying the invention into practical effect, and by reference to the accompanying drawing, illustrating the same and forming a part of this specification.

In the drawing,

Figure 1 is a view in side elevation illustrating the practical application of the invention.

Figure 2 is a view in end elevation showing only the gear unit and the pitman connected balancing cranks.

Figure 3 is an enlarged detail vertical longitudinal sectional view through the crank connected gear unit taken substantially on line 3—3 of Figure 2, and

Figure 4 is an enlarged detail vertical sectional view taken transversely through the crank connected gear unit substantially on line 4—4 of Figure 1.

Referring now to these figures, there is plainly shown a gear unit or reduction gear of the type described and claimed in my above mentioned application and consisting of a support or gear case 10, the lower portion of which forms therein an oil reservoir 11. This case has an annular portion 12 within which is disposed a low speed member in the form of a shaftless gear ring 13, including an outer centrally disposed toothed periphery 14 which faces the inner surface of the annulus 12, and side flanges or extensions 15 which provide outer bearing faces at the sides 40 of, and inwardly beyond, the toothed periphery 14.

Clamping rings 16 are secured around the side edges of the annulus 12 with their inner portions in bearing relation to the side faces of the toothed portion 14 and the outer faces of the ring extensions 15. The low speed gear ring 13 is also shown with an inner annular median rib 17 and its entire area within this rib, which strengthens and braces the ring, may be open and unobstructed since in the present improvements the radial, inwardly projecting crank pin supports of my above application are not needed. The rib 17 provides for the direct connection of weight balanced cranks in a manner we shall

The case 10 is also shown as supporting a high speed shaft 18 with its pinion in engagement with the gear ring 13 at one side thereof, the shaft 18 being driven, for example, by a belt connection to its pulley 19 at one side of the case and closely adjacent thereto so as not to interfere with the swing of the crank arms.

Crank arms 20 are provided by the invention of a type suitably supporting, on their outer laterally enlarged ends, a plurality of weights indicated at 21. These weights are shown in the present instance as held by bolts 22 in a manner permitting of ready addition to or removal from their number.

The crank arms 20 also have series of openings 23 in line for the adjustable reception of the inner or lower bearing pins or supports 24 of the two pitmans 25 so that the throw of the cranks may be readily adjusted to suit the needs of the walking beam 26 in establishing the stroke length of a pumping unit in connection with which the crank balance is used, and to which the upper ends of the pitmans are connected at 27. Such an apparatus commonly involves a Sampson post 28 which supports the beam fulcrum 29 as in Figure 1, and is so well known in the oil well pumping art that the end of the beam from which connections or reins depend to the polish rod of a pump has not been shown.

Each crank arm 20 is furthermore shown as rigidly united at its inner end portion to the outer end of a laterally extending bracket member 30, shown in rectangular, tubular form and at the opposite end of which is an annular clamping ring 31 standing in a plane parallel to, and substantially laterally offset from, the body plane of the crank arm itself. The clamping ring 31 is preferably of an outside diameter slightly less than the inside diameter of the gear ring 13, to seat around, and flatwise against, one side face of the internal rib 17 of said ring as plainly shown in Figure 4. Moreover the clamping ring 31 of each crank arm preferably has a laterally projecting annular flange 32 projecting laterally away from the crank arm and of a width approximately one-half of the width of the gear ring rib 17.

Thus, as shown in Figures 3 and 4 in particular, the outer edge surfaces of the two flanges 32 of opposing crank arms will come together within the gear ring rib 17 and, when connected by an annular series of clamping bolts 33 through the edgewise abutting flanges 32, the two crank arms 20 will be locked together through the gear ring in relatively rotatable relation to the latter. To rigidly connect the joined clamping rings 31, the latter and the gear ring rib 17 have openings therethrough in circumferentially equi-distantly spaced relation, which may be brought into registry for receiving connecting bolts 34 to thus rigidly connect the crank arms 20 directly in driving relation with the gear ring 13. This arrangement makes for ready easy assembly, since the two crank arms may be initially connected to one another through the ring gear and in a manner to readily bring the parts into position for the reception of the connecting bolts 34.

By reason of the provision of the crank arms 20 with laterally offset gear ring connecting portions, the crank arms are properly positioned in laterally offset relation to the gear ring 13, to enable the said arms to properly clear the gear case 10 and its support, in their arc of movement, and also to clear the driving pulley 19, the

gear unit construction making it possible to eliminate the usual axial shaft and reduce by a considerable degree the usual distance between the cranks. This in turn makes it a much easier matter to properly connect the pitmans with the walking beam. It is obvious, furthermore, that by connecting the two crank arms to one another as well as directly to the low speed member of the gear, exact relative positioning of the two crank arms is precisely assured.

With the clamping rings 31 connected by bolts 33 they are held loosely at opposite sides of the rib 17 of the gear ring 13, permitting ready insertion of the bolts 34 through the rib when it is to utilize the weighted crank arms, and for removal when it is desired to rotate the gear without the weighted crank arms.

Having thus fully described the present improvement, what is claimed is,

1. In combination, a speed reduction unit including a shaftless ring-shaped low speed member, and a support therefor in peripheral bearing engagement therewith, crank arms at opposite sides of said unit, means extending through said low speed member and rigidly connecting the inner ends of the two crank arms to each other, and means normally rigidly connecting said first named means to, and within, the low speed member.

2. In combination, a speed reduction unit including a shaftless low speed member in the form of a ring gear, and a support therefor in peripheral bearing relation thereto, crank arms at opposite sides of the unit, means normally extending through the gear and rigidly connecting the crank arms as a unit, and means adjustably connecting said first named means with the gear, whereby the crank arms may be adjusted as a unit annularly within, and with respect to the low speed member.

3. In a crank balance, the combination of a reducing gear unit including a peripherally supported shaftless low speed gear ring, weighted crank arms at opposite sides of said unit, means extending rigidly and laterally from the crank arms within the gear ring, and means circumferentially adjustably connecting said last named means to the gear ring.

4. In a crank balance, the combination of a reducing gear unit including a peripherally supported shaftless low speed gear ring, weighted crank arms at opposite sides of said gear ring, connecting means extending through said gear ring and rigidly joining the crank arms to each other, and means adjustably joining said connecting means with, and entirely around, said gear ring inwardly of the latter.

5. In a crank balance, the combination of a reducing gear unit including a peripherally supported, shaftless, low speed gear ring, and weight carrying crank arms at opposite sides of said unit having portions rigidly connected to and within said gear ring and also having portions rigidly in connection with one another independently of the gear ring connection.

6. In a crank balance, the combination of a reducing gear unit including a shaftless low speed member in the form of a gear ring having a toothed rim portion and an inner annular rib on said rim portion, a support therefor including bearing means for the rim portion of the gear ring, and weighted crank arms at opposite sides of said support having portions at opposite sides of said rib, bolts rigidly connecting said portions with the said rib of the gear ring, and

other bolts rigidly connecting said portions to each other independently of the first mentioned bolts.

7. In a crank balance, a reducing gear unit including a shaftless low speed gear ring having a toothed rim portion and an annular rib within and around said rim portion, a support therefor having a bearing for the rim portion of said gear ring, crank arms at opposite sides of said support having lateral projections rigidly in connection with and adjustable around the rib of the gear ring, and weights on said crank arms.

8. In a crank balance, a reducing gear unit including a shaftless low speed gear ring having a toothed rim portion and an annular rib within and around said rim portion, a support therefor having a bearing for the rim portion of said gear ring, weighted crank arms having offset connecting portions secured directly to and adjustably around said rib of the gear ring, and means connecting said offset portions of the cranks to each other inwardly of the rib and independently of their connections to the rib.

9. In a pump actuator, a reducing gear unit including a shaftless low speed gear ring, a support having a bearing for the peripheral portion of said gear ring and open at opposite sides of the gear ring, crank arms at opposite sides of the gear ring, and means rigidly securing said crank arms in direct connection with the gear ring in- 30

wardly of its peripheral bearing and through the open sides of the support.

10. In a pump actuator, a reducing gear unit including a shaftless, peripherally supported low speed gear ring, open at its center, and crank arms having angular extensions rigidly bolted to, and circumferentially adjustable within, said gear ring at opposite sides of the latter.

11. In a pump actuator, a reducing gear unit including a shaftless, peripherally supported low speed gear ring, open at its center, and crank arms having angular extensions bolted to said gear ring at opposite sides thereof, said extensions being bolted to one another through the open center of the gear ring independently of said ring gear.

12. In a crank balance, the combination of a reducing gear unit including a shaftless low speed gear ring, a support therefor including bearing means in engagement with the periphery of said gear ring, weighted crank arms at opposite sides of said gear ring having laterally extending members projecting into the gear ring at its opposite sides, means normally, rigidly connecting said members to the gear ring, and means normally, rigidly connecting said members to each other independently of said first named connecting means.
